UNITED STATES PATENT OFFICE.

CHARLES JAMES COX, OF NOTTINGHAM, ENGLAND.

ORNAMENTATION OF CLOTH.

SPECIFICATION forming part of Letters Patent No. 317,310, dated May 5, 1885.

Application filed June 10, 1884. (No model.) Patented in England August 24, 1883, No. 4,113; in France February 23, 1884, No. 160,521, and in Germany March 14, 1884, No. 29,434.

To all whom it may concern:

Be it known that I, CHARLES JAMES COX, a subject of the Queen of Great Britain, residing in Nottingham, England, have invented 5 certain new and useful Improvements in the Ornamentation of Cloth, of which the following is a specification.

Hitherto net, lace, and tulle, and other fabrics have been ornamented by dyeing, by 10 printing, by soufflet, (gummed paper,) or by pressing metalized mastic onto the surface as an embellishment on or to the surface, or gum spots by sprinkling, or as beads have been fixed on, and many pleasing and effective designs or devices have been produced thereby; but in all these cases, except in that of dyeing or printing, the body of the fabric has been increased in thickness or bulk, the embellishments being also of a fragile character and liable 15 to lose their brilliancy and spread by climatic action, particularly during damp weather, so as to affect the durability and the consequent utility of the article during use or wear. The purpose of my invention is to obviate 20 these disadvantages and to produce an embellishment or ornamentation of net, lace, muslins, and like open-worked fabrics of a firmer and more permanent character and less liable to be deteriorated by exposure or wear. At 25 the same time no disadvantageous alteration is made in the original thickness of the fabric by my system of ornamentation, as it is applied, without causing protuberances, in such a manner that the embellishments or ornamentations are placed and held within the meshes and are caused to adhere with the requisite firmness to the threads forming the walls of the meshes, the ornamented fabric retaining a flat and level surface on both sides.

30 The adhesive body I prefer to employ for forming my designs or ornaments, applied as hereinafter described, is india-rubber in solution. This being, when dry, pliable and damp-proof it is not liable to crack or spread or detach itself from the fabric. The india-rubber, when in a state of semi-solution and before the solvent has evaporated, is coated with metal in powder or with flock, with silk, or, in fact, with any substance capable of being ap-

plied or affixed to it, or which may attach 50 itself thereon. The india-rubber, or its equivalent, is employed as the ground-work to fill in the meshes and to receive substances or coatings which produces the ornamental effect desired. Where only one color—such as that of 55 gold—is desired, the whole of the ornamental effect for a given length of fabric can be effected at one operation, so as to produce the necessary result; but when two or more colors are necessary in the same given length of the 60 fabric, it will require to be operated upon separately for each color or tint so as to produce the desired effect. In cases where the fabric has comparatively small meshes they may have holes made by piercers, such as will push 65 the surrounding meshes closer together. In the cases of some fabrics pieces may be punched out to form suitable openings into which a suitable viscid body—such as dissolved india-rubber—can be introduced for the after application of powder to the surface or surfaces 70 of the introduced body or material, so as to produce the ornamentation or embellishment of said fabrics, as before set forth.

I do not limit myself to the use of any particular apparatus for carrying my invention into practice. I have found it advantageous to employ pins of the same, or of varying diameters, the pins being so arranged as to conform 75 to the sizes of the openings or meshes and to 80 the pattern in the fabric which I wish to ornament, or to the ornament effect I wish to produce. As an example, as represented in the annexed drawing, which is a side elevation, partly in section, of suitable mechanism, I arrange 85 a number of pins, A, loosely in holes formed in a plate, B, each pin having a head, so that it cannot fall through. These pins (preferably) pass through and project from another or guide-plate, C, to insure their being 90 properly held, and having a vertical action. The two plates B C, with the pins A, are arranged over a bath or trough, D, containing, say, very thin liquid rubber, over which the fabric E is stretched or drawn tight between 95 a give-off roller and a skeleton take-up frame, F, to which an intermittent motion can be given, as required, in any suitable manner.

After leaving the pins, the fabric passes through a heated vessel, G, (preferably,) or a heated plate, and then under a powder-discharging reservoir, H, this having a motion 5 while the fabric E is at rest. Adjacent to the reservoir H, I arrange a pressure-plate, J, beneath which is a table, K, fitted under the upper layer of an endless traveling belt, L, and between this and the take-up frame I fit 10 brushes M M.

The operation is as follows: The pin-carrying plate B has a downward motion, so that the points or free ends of the pins may pass through the meshes of the fabric E; but as the 15 pins are close together some of them may lodge on the threads of the fabric, and should this happen the guide-plate C should be moved, so as to shift the intercepted pins over the meshes, into which they fall for their points or 20 ends to immerse themselves along with the others in the bath of liquid rubber. The pin-carrying plate B is then raised to draw the pins up and out of the bath and up through the meshes of the fabric, the rubber or other 25 solution being rubbed and dislodged from the pins by friction against the threads forming the sides or walls of the meshes and attaching itself within the meshes. The fabric is then moved on a stage, and the part thus operated 30 on enters the heated chamber G, to cause sufficient evaporation of the solvent as to allow of the rubber or other solution being reduced by heat to the required comparatively solid and compact condition, so as to form dia- 35 phragms in the meshes operated upon. The fabric, as it leaves the heated chamber, passes over without touching the endless belt L of sheet-rubber, and under without touching the suspended powder-reservoir H, which has a 40 motion imparted to it. The mouth of the reservoir rests and slightly scrapes upon a fine screen, through which the powder passes. The powder is caused to fall in a shower upon the fabric at the part where the liquid rubber has 45 been applied and adheres to the applied solution, some of it falling through the open meshes, which have not had the rubber applied, onto the rubber belt beneath. The belt L is set at an incline and at its higher level passes

over and in contact with a table or perfectly 50 flat slab, K, this having a press-head or force, J, above, which can descend and exert a pressure on the fabric, so as to put the under surface of the fabric into contact with the powder which is upon the belt, so that the then nearly 55 dry rubber in the meshes may take and be be coated with it, and at the same time be slightly embedded into both surfaces. The pressure is relieved and the tension of the fabric lifts it from the table, so that the fabric may 60 pass on another stage and between a pair of revolving brushes, M M, which remove the superfluous powder before the fabric is wound upon the skeleton frame F. The endless belt 65 L works in a vessel or box, P, and the powder on it not taken up by the rubber in the meshes falls from it into the box and is collected to be returned to the reservoir H, when necessary.

I claim as my invention—

1. The within-described method of ornamenting fabrics having perforations or openings therein, consisting in applying a viscid substance to the inner edges or surfaces of said openings and then applying a powdered sub- 75 stance to such viscid substance within the openings or perforations without increasing the thickness of the fabric, substantially as described.

2. The within process of applying a viscid substance to a perforated or apertured fabric to prepare it to receive further ornamentation, consisting in applying said viscid substance to the inner edges or surfaces of the openings in the fabric without applying it to 85 the outside surface of the fabric, substantially as described.

In witness whereof I have hereunto signed my name in the presence of two subscribing witnesses.

CHARLES JAMES COX.
